Patented Jan. 10, 1922.

UNITED STATES PATENT OFFICE.

JOSEPH S. OTT, OF THE UNITED STATES ARMY.

SECURING MEANS FOR SPIRAL PUTTEES AND THE LIKE.

1,402,952.

Specification of Letters Patent. Patented Jan. 10, 1922.

Application filed May 6, 1921. Serial No. 467,486.

To all whom it may concern:

Be it known that I, JOSEPH S. OTT, a citizen of the United States of America, United States Army, have invented certain new and useful Improvements in and Relating to Securing Means for Spiral Puttees and the like, of which the following is a specification.

This invention relates to certain improvements in and relating to securing means for spiral puttees and the like; and the nature and objects of the invention will be readily understood by those skilled in the art in the light of the following explanation and description of the accompanying drawings illustrating what I now believe to be the preferred embodiment or mechanical expression of my invention from among other forms, embodiments and constructions within the spirit and scope thereof.

One type of spiral puttee which is in universal use embodies a strip or band of non-elastic material adapted to be wound spirally around the leg of the wearer, usually from the ankle upwardly to a point below the knee, and the length of non-elastic fastening tape secured to that end of the non-elastic strip or band which forms the last turn on the leg. In use the puttee is wound around the leg and several turns of the fastening tape are taken over and around the last winding of the strip or band forming the puttee, and the end of the tape is either forced under the last winding of the band, or it is forced under, between or around the several turns of the fastening tape, to secure the puttee in proper position upon the leg.

In applying this type of non-elastic puttee it is necessary to wind the puttee around and onto the leg with a certain amount of tension so that it will snugly fit and conform to the shape of the leg but without binding the leg or stopping the circulation. Experience has shown those familiar with the use of this non-elastic type of puttee, that when the puttee is wound onto the leg with the proper amount of tension, and the fastening tape is in puttee securing position therearound with the end of the tape forced under the last winding of the puttee or under the turns of the tape, the use by the wearer in walking or other exercise of the leg, causes the puttee to lose the tension with which it was wound onto the leg and to come par-

tially unwound, or causes the end of the fastening tape to come unsecured and permit the puttee to completely unwind and sag or fall from the leg. This loss of tension in the puttee as applied, is due to the curve and contour of the leg over which the puttee is wound, and to the pressure exerted on the puttee by movement of the leg and consequent expanding and contracting of the leg muscles.

The pressure exerted by the movement of the leg pulls upon the windings of the puttee and draws the tucked or forced in end of the fastening tape from secured position and results in the displacement, sagging or unwinding of the puttee as referred to.

After the operation of winding the puttee upon the leg and taking the several turns of the fastening tape around the last winding of the puttee, it is necessary to firmly hold the fastening tape with one hand in order to maintain the proper tension upon the puttee, while forcing the free end of the winding tape under the last winding of the puttee or between the turns of the tape, to secured position with the other hand. Any attempts to tie the end of the tape or take several turns between the turns of the tape necessitates use of both hands and release of tension of the puttee, as well as being impractical when the puttee is removed.

The present invention has particular reference to spiral puttees of the non-elastic type, such as hereinbefore referred to, and contemplates the provision of securing means at the ends of the fastening tapes of non-elastic puttees for securing the tapes and puttees in position upon the legs of the wearer. The invention includes among its objects; to provide a simple, removably attached securing means on the ends of the fastening tapes of non-elastic puttees which can be readily secured in operative puttee securing position, and detached therefrom, by slight pressure of one hand of the user; to provide such means in the form of a hook formed of a single piece of material and adapted for removable attachment to all forms of fastening tapes of the general type of the non-elastic puttee hereinbefore identified, without requiring any material changes in form or arrangement of existing tapes; to provide securing means for the above type of spiral puttees which permit securing the fastening tapes and puttees in position upon

the legs with the proper amount of tension and without the possibility of the tapes becoming unfastened and the resulting displacement or unwinding of the puttees; to 5 provide securing means for puttees of the above type which overcome and avoid the various disadvantages and inconveniences hereinbefore pointed out as inherent in the existing forms of this type.

10 With these and other objects in view the invention consists in certain novel features in construction and in combinations and arrangements as more fully and particularly set forth and pointed out hereinafter.

15 Referring to the accompanying drawings:

Fig. 1 is a perspective view of a leg having a spiral puttee of the non-elastic type wound thereon and provided with an embodiment of the securing means of my invention attached thereto and maintaining the puttee in applied position.

20 Fig. 2 is a perspective view of the invention applied to the end of a fastening tape and showing a portion of the body or band 25 of the puttee.

Fig. 3 is an enlarged perspective view of the securing means of the invention, showing in dotted lines the end loop formed on the fastening tape in which the means is 30 confined.

Fig. 4 is an end elevation of the securing means of the invention detached from the puttee.

Fig. 5 is a top plan view of the securing 35 means of the invention detached from the puttee.

In the accompanying drawings I show one form of non-elastic spiral puttee as illustrative of the general type to which the present 40 invention has particular reference, and it is to be understood that I do not desire or intend to limit the invention to the combination and use with the specific shape and form of puttee disclosed in the accompanying 45 drawings by way of a designation of this general type.

The illustrated example of a puttee to which the invention is applicable by combination and use therewith, comprises the strip 50 or band 1 of non-elastic material and the comparatively narrow length of non-elastic fastening tape 2, of considerable length with respect to the band 1, which arrangement is well known and understood by those familiar with this art. In Fig. 1, of the accompanying drawings, I show the puttee applied to the leg A of the wearer by winding the band 1 spirally upwardly around the leg A, from a point just below the knee, and 55 forming the partially overlapping windings 1^a completely covering the leg, as hereinbefore referred to and explained. The end of the upper or last winding of the band 1 has the fastening tape 2 secured thereto, and 60 in applied position several turns of the tape

2 are taken around the upper winding 1^a to secure the puttee in proper applied position on the leg, as clearly shown in Fig. 1 of the drawings.

The invention provides securing means 3 70 removably secured in an eye or loop 2^a which is formed at the free end of the fastening tape 2 and adapted to removably receive and confine the means 3 to the end of the tape 2. The securing means 3 is preferably 75 formed of a single piece of material and comprises the bar 3^a having the ends thereof turned inwardly to provide the tape retaining lengths 3^b extending a distance along, parallel with, and spaced from the bar 3^a. The retaining lengths 3^b terminate a distance apart in similar hooks consisting of the shanks 4 and the bills 4^a. The shanks 4 of these hooks are at approximate right angles to the bar 3^a and substantially parallel 85 with each other and provide a space 5 therebetween through which the loop 2^a of the tape 2 is passed in removing and attaching the securing means 3 from and to the tape 2.

80 The bills 4^a of the hooks are formed with 90 sharpened points for easy insertion into the material of the tape 2 and also have a slight inward curve or bend toward the bar 3^a. The effect of the foregoing construction is to provide a loop having an opening 5 at one 95 side and a pair of parallel hooks, spaced apart and extending outwardly from the open side of the loop.

The loops 2^a of the fastening tapes 2 are formed by turning back the free ends of the 100 tapes and sewing, or otherwise securing these ends to the bodies of the tapes, respectively. One of the many advantages of puttees formed of non-elastic material consists in the fact that such material may be freely 105 washed without in any manner damaging or spoiling the puttee, and the provision of the loops 2^a at the ends of the fastening tapes of the puttees permits of the ready removal and attachment of the securing means of the 110 invention when it is desired to wash the puttees. The securing means 3 are attached to the fastening tapes by passing the loops 2^a through the opening 5, which are of less width than the tapes, then extending the 115 loops to normal width with the bights thereof confined around the bars 3^a by the retaining lengths 3^b, as will be clearly understood by reference to Figs. 2 and 3 of the drawings. The removal of the securing means 3 120 is performed in the same manner by passing the loops between the openings 5 and withdrawing the means 3 therefrom.

In the use of non-elastic puttees provided with the securing means of the invention as 125 described, the bands 1 are wound upon the legs of the wearer in the usual manner and several turns of the fastening tapes 2 are taken around the last windings of the bands, then the bills 4^a of the hooks are forced into 130

the turns of the tapes therebeneath, respectively, by slight pressure of a hand of the wearer, and the puttees are fastened into proper applied position. It is understood 5 that the securing means 3 are so attached to the fastening tapes 2, that with the puttees in applied position, the bills 4^a of the hooks extend inwardly toward the turns of the tapes therebelow. In order to remove the 10 puttees when fastened as described above, it is only necessary to apply slight under pressure, with the thumb, for example, to the under sides of the fastening tapes 3 and draw or force the hooks from engagement with the 15 tapes. After the hooks are disengaged the puttees may be removed and rolled in the usual manner.

The provision of the double hooks in each 20 securing means prevents lateral movement and the possibility of the ends of the tapes becoming unfastened when unequal forces or pressures act on one edge or the other 25 of the ends of the tapes.

It will be noted that the bills 4^a of the 25 hooks are of comparatively short length in order to prevent blows or pressure from forcing them through the thicknesses of the fastening tape and band of the puttee therebelow into the leg of the wearer.

30 As hereinbefore explained, it is necessary to apply non-elastic puttees with the proper amount of tension and it was pointed out wherein the manner of securing the existing non-elastic types presented certain difficulties and disadvantages, so that it will be readily seen and understood that in applying puttees provided with the securing means of the invention they may be wound upon the leg with the desired tension and 35 then by a single movement and slight pressure of the hand be instantly fastened on the leg without varying the desired tension. In use upon the wearer, the pressure exerted by the various positions of the legs and the 40 expanding and contracting of the muscles, aided by the slight curve of the hooks, will firmly maintain the fastening tapes securely fastened with the puttee in applied position and without the ever present possibility of 45 the puttee sagging or unwinding as with the existing types of non-elastic puttees.

50 Although particularly applicable to and overcoming the disadvantages of the prevailing types of non-elastic puttees, the present invention may be applied to elastic puttees with satisfactory results, although such puttees have been found very unsatisfactory and generally impractical by those familiar with and using spiral puttees.

60 It is also evident that various modifications and departures might be resorted to without departing from the spirit and scope

of my invention and hence I do not wish to limit myself to the exact disclosure hereof.

Desiring to protect my invention in the 65 broadest manner legally possible, what I claim is:

1. Securing means for spiral puttees, comprising a bar having retaining lengths substantially parallel with and spaced from 70 said bar, the said retaining lengths extending inwardly toward each other along the major portion of the length of said bar and terminating a distance apart adjacent the central portion of said bar to provide a space 75 between the ends thereof, the said bar adapted to be inserted through the end loop of a spiral puttee fastening tape with said retaining lengths extending exteriorly and transversely across the tape to confine said 80 bar thereto against movement transversely thereof, and spaced hooks extending from said retaining lengths for engagement with the adjacent turn of the puttee fastening tape to secure the puttee in wrapped position. 85

2. Securing means for spiral puttees, comprising a bar adapted to be inserted through the end loop of a spiral puttee fastening tape, retaining lengths extending from the ends 90 of said bar inwardly toward the center thereof and adapted to lie on the exterior and transversely of the fastening tape loop, said retaining lengths extending inwardly toward each other along said bar, substantially 95 parallel therewith and spaced therefrom, to and terminating a distance apart, and spaced hooks extending outwardly from the inner ends of said retaining lengths, respectively, the said hooks comprising shanks and relatively short, slightly 100 inwardly turned hooks adapted to engage the adjacent under turns of a puttee fastening tape in wrapped position of the puttee. 105

3. Securing means for spiral puttees, comprising a bar, retaining lengths extending from the end portions of said bar inwardly toward each other along said bar substantially parallel therewith and spaced therefrom, the said retaining lengths terminating 110 a distance apart and forming spaces along and between said bar and retaining lengths, and spaced hooks extending outwardly from the inner ends of said retaining lengths, the said hooks comprising shanks, and bills 115 slightly turned inwardly toward said retaining lengths, the spaces between said retaining lengths and said bar adapted to receive a puttee and a space between the ends of said lengths and said hooks providing for 120 the passage of the puttee in removing the same to and from the spaces along said bar.

JOSEPH S. OTT.
